CLAIM

The ornamental design for a seal cap, as shown and described.

DESCRIPTION

FIG. 1 is a front, top-side perspective view of the seal cap showing our new design;

FIG. 2 is a back, bottom-side perspective view thereof;

FIG. 3 is a top view thereof;

FIG. 4 is a bottom view thereof;

FIG. 5 is a first side view thereof; and,

FIG. 6 is a second side view thereof which is rotated 90° with respect to the first side view shown in FIG. 5.

The broken lines are shown for the purpose of illustrating parts of the article that form no part of the claimed design.

1 Claim, 4 Drawing Sheets
